CHARLES JOHN HAUK, JR., OF YONKERS, NEW YORK.

CLOSURE FOR TUBES.

Application filed December 30, 1920. Serial No. 434,102.

To all whom it may concern:

Be it known that I, CHARLES JOHN HAUK, Jr., a citizen of the United States, and a resident of Yonkers, in the county of West-
5 chester and State of New York, have invented a new and Improved Closure for Tubes, of which the following is a full, clear, and exact description.

The present invention relates to new and 10 useful improvements in collapsible tubes, and it pertains more particularly to a closure therefor.

It is one of the objects of the present invention to provide a closure for tubes in 15 which the ordinary screw-thread commonly employed in a device of this character, is dispensed with, the tube neck and cap being so constructed as to lock with a partial turn of one relative to the other.

20 It is a further object of the invention to provide means whereby the cap cannot become entirely removed from the tube thereby preventing accidental loss of the cap.

It is a still further object of the invention 25 to provide such captive means for the cap as will not interfere with the free and easy operation of placing and removing the cap.

Referring to the drawings—

30 Fig. 1 is a detail sectional view of a slightly modified form of the invention showing in full lines the closure in closed position, and in dotted lines the closure in open position;

35 Fig. 2 is a top plan view showing in full lines the closure in open position, and

Fig. 3 is an inverted plan view of the closure.

In the drawings the tube 10 is provided 40 with a groove 30 in its upper portion adjacent the base of the neck 11. This groove is arcuate in form and circular in cross sec-

tion, and it is provided intermediate of its ends with notched out portions 31, the purpose of which will be hereinafter described. 45

The cap 15 is provided with a depending leg 29 upon the lower end of which is a T-head 32, said T-head being circular in cross-sectional form and adapted to be received within the groove 30 for sliding 50 movement longitudinally thereof. The groove 30 is notched out as at 31, as herein-after described, for the purpose of permitting of the insertion of the T-head 32 into the groove 30. The groove 30 is further 55 notched out as at 33, and said notched out portion 33 is adapted to receive the stem 29 of the cap 15, when the cap is moved to the open position as shown in Fig. 2.

From the foregoing it is apparent that the 60 present invention provides a new and novel closure for tubes, and that the construction thereof permits of a closing of the tube with only a partial rotation of the tube and cap relative to each other.

Furthermore, the invention provides 65 means for retaining the cap on the tube in proximity to the closure thereof in order that the same may not become accidentally displaced and lost.

I claim:

In a tube closure, a tube, an elongated recess formed in the neck of said tube and of substantially circular cross sectional form, the top walls of said recess having a cut-out 75 portion intermediate of its ends, a closure cap, and means in the form of a headed stop carried by said cap and having sliding engagement with the recess of the tube to retain the cap in position upon the tube, said 80 headed stop being insertable into the elongated recess through the cut-away portion intermediate of its ends.

CHARLES JOHN HAUK, JR.
